UNITED STATES PATENT OFFICE.

LUTHER L. BLAKE, OF CRANFORD TOWNSHIP, UNION COUNTY, NEW JERSEY, AS
SIGNOR TO STANDARD STATISTICS COMPANY, OF NEW YORK, N. Y., A CORPORA-
TION OF NEW YORK.

SUPPLEMENT HOLDER FOR BOOKS.

Application filed December 8, 1920. Serial No. 429,100.

To all whom it may concern:

Be it known that I, LUTHER L. BLAKE, a citizen of the United States, and a resident of the township of Cranford, in the county 5 of Union, State of New Jersey, have invented certain new and useful Improvements in Supplement Holders for Books, of which the following is a specification.

The improvements relate to the book binding art, and more particularly to bindings for books containing matter which is supplemented, amended, or added to after the publication of the original volume, and the objects of the improvements are primarily 10 to provide a cover for such a book which will serve all the ordinary uses and purposes of such a cover, and which will also provide means for adding to such volume and connecting therewith in proper position and 15 relation one or more supplements or addenda. In carrying out these improvements the cover of the original volume and the cover of the supplement are made of such size and form that they coordinate with each 20 other and in such a manner that the reading matter—which may be in any ordinary style and type—is arranged in proper relation and sequence.

Examples of such publications are lists of 25 bonds and other securities, which change in value or in other respects interesting to the investor, and concerning which the average investor desires to have up to date information; lists of reports or decisions which are modified or otherwise affected by later 30 reports or decisions; and codified or digested laws, decisions or rulings, which are subject to later amendment, change, or interpretation.

Volumes containing such matter are published and are used by various classes of 35 persons and for various purposes, and supplements giving later information affecting the matter in the original volume are frequently published later, and usually at 40 stated periods, for the information of those who have the original publication; and it is important that the original volume and the supplement giving later information concerning 45 its contents shall be connected and associated in such a manner that one will, and may conveniently, be consulted with the other. Information of "service" of the kind indicated is usually sold by subscrip-

tion, the subscription entitling the subscriber to an original volume and supplements thereto published quarterly, semi-annually, or regularly after the lapse of some other specified period, and the subscriber is usually instructed to consult the supplement 55 before or after reading the particular portion of the original volume in which he may be interested. But it frequently happens that supplements are lost or mislaid or the wrong supplement is consulted; and it is 60 therefore important that the original volume and the proper supplement shall be so connected and arranged that this cannot happen if ordinary care be exercised. The 65 principal object of the present improvements is therefore to provide for the proper and secure, yet quickly detachable connection and association of a volume and one or more supplements thereto, so that both may 70 be treated practically as one volume and 75 consulted as one work.

The improvements are illustrated in the accompanying drawings, referred to herein, and in which Figure 1 is a side elevation of 80 a bound volume and supplement embodying the improvements; Figure 2 is a like view of the same with the supplement turned out to expose the cover of the book, and a portion of the book cover broken away to show 85 the connection between book and supplement; Figure 3 is a transverse section on the line 3—3 of Figure 1, as indicated in that figure; Figure 4 is an enlarged detail in cross-section of the front of the book cover, as illustrated in Figure 3.

The book consists of the desired number of signatures 1, bound at one edge as indicated at 2, and united at the back 5 with a case cover comprising boards 3 and cover of 90 cloth or other suitable material 4.

The portion of the cover 4^a which extends over the outer face of the front board 3 is not secured thereto, but has its inturned edges glued to the inner face thereof and is otherwise free from the said board. It has however a sheet of thin fibre board 6 or other similar material pasted to its under side, and has its inner edge turned over and pasted along the under side of this sheet. 100 This sheet 6 is not connected with the front board except through the material of the front cover as just described, thus leaving a 105 pocket between the reinforced cover and the

front board of the case cover, and as the cover 4^a is not secured to the outer face of the board and along the inner edge is secured only to its reinforcing strip a mouth 5 for this pocket is thus provided along the hinge or joint 7 and slightly forward thereof.

The supplement consists of leaves 8 secured at one edge to the back of a cover 9 10 preferably of tough paper, and the back of this cover 9^a is cut short of the outer edges of the leaves and tapered from a point near the back to its outer edge, so as to form a tongue or flap to be inserted in the pocket. 15 In order to secure the supplement to the book it is only necessary to slip the tongue 9 in the pocket as far as it will go, and in this position the back of the supplement cover will be aligned with the joint or hinge 20 7 of the book and the flap held by frictional coaction and contact of its top and bottom edges with the inside edges of the pocket against movement in all directions. When the supplement is opened the back will 25 enter the depression at the joint, and at all times the bead or ledge 10 will aid in preventing the supplement from slipping out of position. To remove the supplement it is only necessary to draw the tongue or flap 30 9^a from the pocket, and a supplement may be removed and a new one inserted in its place in a few moments. In case it should become necessary or advisable to add a new supplement without removing a previous 35 one this can be done by simply inserting the tongue of the new supplement in the pocket beneath the tongue of the old supplement. The supplement is made slightly smaller than the cover of the original volume, but 40 the leaves are of substantially the same length as the leaves of the original, and only slightly narrower so that the volume with one or more supplements or addenda has substantially the appearance and the 45 convenience of a single volume.

The reinforcing sheet 6 of the covering material 4^a is normally in contact with the outer surface of the front board so that anything inserted in the pocket will be held 50 therein by the covering material which must be stretched to some extent to receive it, and as the pocket is therefore too small to receive the supplement it is not possible for the user to insert the supplement 55 therein. The printing matter of the volume and supplement is arranged in the usual manner so as to read from front to back, and as the pocket is on the exterior of the front cover and the tongue is on the 60 back of the supplement, when the tongue is inserted in the pocket the volume and supplement will be in proper position and relation to each other.

What I claim is:

65 1. A book and supplement comprising a

volume having leaves bound together at one edge and secured at said edge to a case having a back with laterally projecting edges and front and back covers, a pocket formed by a piece of covering material secured to the outside of the front cover only along the front, top and bottom edges thereof and opening at the edge adjacent the back, and a supplemental volume consisting of leaves secured together and a tongue to which said leaves are secured along one edge, said tongue extending from said edge toward the opposite edge and formed to fit said pocket, and the edges of the tongue and leaves which are secured together being adjacent to and inside the side edges of the back.

2. A book and supplement comprising a volume having leaves bound together at one edge and secured at said edge to a case having a back and front and back covers, a pocket formed by a piece of covering material secured to the outside of the front cover only along the front, top and bottom edges thereof and having its mouth at the edge adjacent the back, and a supplemental volume consisting of leaves secured together and a tongue to which said leaves are secured along one edge, said tongue extending from said edge toward the opposite edge and formed to fit said pocket, and said back having a bead normally opposed and in proximity to the mouth of the pocket and the back of the supplemental volume when in place.

3. A book and supplement comprising a book proper, consisting of leaves and a cover to which the said leaves are bound along one edge, a back to which said edges are secured, said back having a side portion extending beyond the outer surface of the cover along its bound edge, a pocket on the exterior of said cover having its opening in proximity to the bound edge of the cover and within the extending portion of the back, and a supplement comprising leaves bound together at one edge, a tongue bound to said leaves at the same edge and formed to fit said pocket, the said supplement leaves being formed and arranged to lie on the outside of said pocket when the tongue is therein and to open at the same edge as the leaves of the book, but being openable without opening the book cover.

4. A book and supplement comprising a main volume consisting of leaves and a front and back cover bound together near one edge in such a manner as to leave a projecting ridge extending beyond the outer surface of a cover along the said edge, a pocket formed on the exterior of the said cover and having a mouth adjacent to and substantially parallel with said ridge, but spaced therefrom a sufficient distance to accommodate the back or bound edge of a sup-

plement, a supplement also consisting of leaves bound together near one edge and a cover bound therewith along the said edge forming a tongue of a size and shape to fit 5 the said pocket, the said supplement having a portion extending from said binding to its adjacent edge of a size and shape to fit between the mouth of said pocket and the said ridge of the main volume, whereby the

supplement is held normally against movement in all directions in position on the main volume, but may be removed therefrom and replaced by flexing the materials with the fingers.

Witness my hand this 30th day of November, 1920, at the city of New York, in

the county and State of New York.

LUTHER L. BLAKE.
